UNITED STATES PATENT OFFICE.

WARREN C. BROWN, OF TARRYTOWN, NEW YORK.

INSULATOR.

SPECIFICATION forming part of Letters Patent No. 398,025, dated February 19, 1889.

Application filed December 28, 1888. Serial No. 294,832. (No model.)

To all whom it may concern:

Be it known that I, WARREN C. BROWN, of 5 Tarrytown, in the county of Westchester and State of New York, have invented a new and Improved Insulator, of which the following is a specification, reference being had to the annexed drawings, forming a part thereof, in which—

Figure 1 is an end elevation of my improved 10 insulator. Fig. 2 is a side elevation of the same. Fig. 3 is a side elevation taken at right angles to the plane of Fig. 2, and Fig. 4 is a side elevation of one-half of the insulator.

Similar letters of reference indicate corresponding parts in all the views.

The object of my invention is to provide a simple and efficient insulator for receiving 15 electrical conductors and holding them firmly without the necessity of using binding-wires 20 or of twisting them together.

My invention consists in an insulator formed of two halves, each provided with a semicircular groove, one half being furnished with a lug and the other with a recess for causing 25 the grooves of the two halves to register and clamp upon the wire.

My improved insulator consists of the two 30 halves A B, which together form a cylinder, with a transverse aperture, *a*, for receiving the wire *b*, and with an axial countersunk hole, *c*, for receiving the screw *d*, which supports the insulator in the position of use. The halves A B of the insulator are each provided with a semicircular groove, *e*, the two grooves when 35 the halves of the insulator are clamped together forming the transverse aperture *a* for receiving the wire *b*.

A recess, *f*, of trapezoidal shape, is formed in the part B of the insulator to cause the

grooves *e* to register, and upon the part A is 40 formed a projection, *g*, of corresponding shape, which fits into the trapezoidal recess when the two halves are clamped together. The projection *g* extends from the periphery of the part A to a point beyond the screw-hole *c*, 45 thereby insuring the perfect insulation of the screw *d* from the wire *b*, as clearly indicated in dotted lines in Fig. 2. Arranged in this way the distance from the wire *b* to the screw *d* is increased, so that an ordinary battery- 50 current could under no circumstances leap off to the screw. This construction also prevents the entrance of moisture into the portion of the insulator where the screw passes the division line of the two parts of the insulator. 55

My improved insulator may be made of glass, porcelain, vulcanite, or any of the materials usually employed for this purpose.

Having thus described my invention, I claim as new and desire to secure by Letters Patent— 60

1. An insulator formed of the two halves A B, bored axially and adapted to receive the screw *d*, one half being furnished with the recess *f* and the other half being provided with a projection, *g*, fitted to the recess and adapted 65 to shut off leakage from the wire to the screw, substantially as specified.

2. As an improved article of manufacture, an insulator formed of the halves A B, provided with the semicircular grooves *e*, the part B being provided with a recess, *f*, and the part A having a projection, *g*, which extends beyond the screw-hole *c*, substantially as specified. 70
